UNITED STATES PATENT OFFICE.

JESSE HENLEY ALEXANDER, OF WILLIAMSTOWN, MISSOURI.

DESIGN FOR A REIN-GUIDE FOR HARNESS.

SPECIFICATION forming part of Design No. 35,896, dated May 6, 1902.

Application filed March 22, 1902. Serial No. 99,552. Term of patent 7 years.

To all whom it may concern:

Be it known that I, JESSE HENLEY ALEXANDER, a citizen of the United States, residing at Williamstown, in the county of Lewis and State of Missouri, have invented and produced a new and original Design for a Rein-Guide for Harness, of which the following is a specification.

The present invention relates to rein-guides for harness; and the object thereof is to provide a design of this character which is new, useful, original, and ornamental.

The leading features of the design reside in an open base-frame made of angularly-disposed longitudinal and transverse bars, ears projecting from opposite portions of the side edges of the base-frame, with strap-engaging openings made in the ends of the frame and in the ears, and an upstanding longitudinally-disposed rein-guide frame projecting from the base and comprising oppositely-disposed guide-loops, the inner ends of which are spaced apart and are connected by a cross-arm upon which is located an ornamental head that is secured to the arm by a contracted neck and has artistically-arranged eyes or openings therethrough.

The drawing is a perspective view of the new design.

It will be seen by reference to this draw-

ing that a base-frame 1 is provided comprising longitudinal spaced bars 2, which are connected by transverse bars 3, the intermediate bars 3 projecting beyond the outer longitudinal bars and being connected at their ends to form ears 4. Strap-receiving openings 5 are made in the ends of these ears and also in the ends of the base-frame. From an intermediate portion of the base-frame projects an upstanding longitudinally-disposed rein-guide frame comprising oppositely-disposed guide-loops 6, the inner ends of which are spaced apart and connected by a cross-arm 7, upon which is arranged an ornamental head 8, that is connected to said cross-arm by a contracted neck 9 and is provided with artistically-shaped openings 10.

Having thus described my invention, what I claim as new, and desire to secure by Letters Patent, is—

The design for a rein-guide as herein shown and described.

In testimony that I claim the foregoing as my own I have hereto affixed my signature in the presence of two witnesses.

JESSE HENLEY ALEXANDER.
